UNITED STATES PATENT OFFICE.

ISAAC E. PALMER, OF MIDDLETOWN, CONNECTICUT.

DESIGN FOR A HAMMOCK.

SPECIFICATION forming part of Design No. 23,309, dated May 22, 1894.

Application filed April 13, 1894. Serial No. 507,488. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawings, forming a part thereof.

The leading feature of my design consists
o in the shape of the hammock provided with
the outer shallower valance extending from
the opposite sides of the body of the ham-
mock and the deeper inner valance, also ex-
tending from the opposite sides of the ham-
mock, forming flounces at the sides of the
hammock, as shown.

Figure 1 represents the parts in the position they assume when spread out in a plane, and Fig. 2 represents the parts as they appear when the hammock is strung for use. ²⁰

A represents the body of the hammock, a
the shallower outer valance, and B the deeper
inner valance.

What I claim is—

The design for a hammock, substantially as ²⁵
herein shown and described.

ISAAC E. PALMER.
